DRILLING TOOL.

Application filed February 9, 1924. Serial No. 691,817.

This invention relates to drilling devices, especially adapted for use in connection with the rotary system of drilling.

One of the principal obstacles encountered in rotary drilling resides in the fact that the producing sands may be unconsciously drilled through and passed and thus the drilling operation is a total loss.

Therefore, an important object of this invention is to provide novel means whereby samples of the formation may be frequently taken so that the possibility of unconsciously drilling through the producing sands or strata is reduced to a minimum.

A further object is to provide a combined bit and sampling tool which drills a hole of a uniform diameter throughout so that the necessity of reaming the lower portion of the hole subsequent to taking a sample is overcome.

Further the invention aims to provide a combined bit and sampling tool having simple means to prevent the loss of a sample of the formation and which is provided with means whereby the sample is preserved as long as the run continues.

Other objects and advantages of the invention will be apparent during the course of the following description.

In the accompanying drawing forming a part of this application, and in which like numerals are employed to designate like parts throughout the same,

Figure 1 is a side elevation of the improved cutting and sampling tool;

Figure 2 is a similar view, the view being taken at right angles to Figure 1;

Figure 3 is a central vertical longitudinal sectional view through the improved tool;

Figure 4 is a transverse sectional view taken on line 4—4 of Figure 2;

Figure 5 is a transverse sectional view taken on line 5—5 of Figure 3;

Figure 6 is a horizontal sectional view taken on the line 6—6 of Figure 3;

Figure 7 is a side elevation of one of the blades or cutters embodied in the invention.

In the drawings wherein for the purpose of illustration is shown a preferred embodiment of the invention, the numeral 5 designates a body having a longitudinal bore 6 which constitutes a sample receiving chamber.

Figure 3 illustrates that the forward portion of the body is provided with oppositely arranged recesses 7 to snugly receive the at-

taching portions 8 of reaming cutters 9. In carrying out the invention the attaching portions of the cutters are formed with openings aligned with similar openings in the body 5 to snugly receive fastening bolts 10. With reference to Figure 1 it will be observed that the head 11 of each fastening bolt 10 is provided with a squared opening for the reception of a tool by means of which the bolt may be either fastened or loosened. Of course the opening in the head 11 may be triangular or any other shape which will allow the tool to have a gripping engagement with the bolt. Also the body 5 is counterbored to receive the enlarged head of the bolt 10 so that no portion of the bolt projects beyond the periphery of the body.

Figures 1 and 3 illustrate that the blades or cutters 9 extend beyond the periphery of the body 5 and constitute the major cutters in the device and are more or less of fish-tail design. Also the cutters 9 are on opposite sides of the head 12 and constitute a protecting means for the same. The head 12 has threaded engagement with a nipple 14 which receives slips 16 by means of which the formation or sample is prevented from dropping out of the lower end of the tool during the withdrawal of the tool to the surface.

The nipple 14 is provided on its inner side with an inclined wall by means of which the teeth of the slips 16 are urged into engagement with the formation. That is to say, the bore of the nipple 14 is tapered at its upper portion so that as the slips descend they will be urged into engagement with the formation. The descent of the slips in the nipple 14 is limited by means of an annular shoulder 18 directly beneath the tapered portion of the bore of the nipple. The upward movement of the slips is limited by the lower end of the head 12 and it is thus seen that the longitudinal movement of the slips is limited. Furthermore, the slips 16 are held in position with relation to each other by means of oppositely arranged ribs 20 extending inwardly from opposite sides of the internal wall of the nipple.

The forward portion of the member 14 is formed with a threaded extension to which a cutter head 22 is connected and the said cutter head is provided with approximately triangular cutting members 24 which define an annular cut and thereby allow the sample to enter the sample-receiving chamber.

In the case of an ordinary well of about fourteen inches in diameter a four inch sample may be taken and as the width of the wall of the cutter head 22 is one inch the total cut made by the cutter head will be six inches. In addition to this, the reaming cutters 9 will make four inch cuts so that the total diameter of fourteen inches is provided for.

10 In operation, the drilling is started in the usual manner and the sample enters by way of the cutter head 22 and the nipple 14, and the run may continue for as long as desired. At any time the formation may be tested and 15 thus the possibility of drilling through the producing sands is overcome.

Of course any size tool may be employed and the cutting area of the members 9 and the members 22 may be varied as the occasion requires.

In carrying out the invention the inner walls of the recesses 7 are provided with projections 40 adapted to be received in recesses 42 in the inner edges of the attaching portions 8 of the cutters 9. By reason of this construction the body 5 is strengthened and the connection between the attaching portions 8 and the body 5 is also strengthened.

30 The cutter head 22 is provided with internal grooves 50 having communication with radial openings 52 for the passage of the fluid by means of which the drilling is facilitated. In carrying out the invention 35 any number of cutters may be employed.

Having thus described the invention, what is claimed is:

1. In a device of the character described, a cutter carrying body or head having longitudinally extending grooves at its lower end, a plurality of cutters each having a shank extending therefrom and fitted into one of said grooves, a pair of securing bolts for each cutter shank, said bolts extending laterally through the walls of the body member and through the cutter shanks, and each pair of bolts securing a shank being spaced longitudinally of the cutter body, and a lug carried by the body for each shank, each lug being located to fit into a recess in the associated cutter shank at a point intermediate the securing bolts for said shank.

2. In a device of the character described, a nipple, interiorly threaded at its upper end and adapted to be threaded upon a tool carrying body member, the bore of the nipple being flared outwardly from a point adjacent its lower end and in an upward direction, diametrically disposed ribs formed upon the outwardly flared portion of the nipple bore adapted to form a pair of opposed runways, and a pair of core retaining members each comprising a block arcuate in shape and adapted to slidably fit within runways formed by the ribs, the upward movement of the core retaining members being limited by the associated end of a tool carrying body to which the upper end of the nipple may be threaded.

PERCY BRUNT.
